UNITED STATES PATENT OFFICE.

GEORGE H. GARCELON, OF SWISSVALE, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed August 12, 1922. Serial No. 581,317.

To all whom it may concern:

Be it known that I, GEORGE H. GARCELON, a citizen of the United States, and a resident of Swissvale, in the county of Allegheny and State of Pennsylvania, have invented a new and useful Improvement in Short-Circuiting Devices, of which the following is a specification.

My invention relates to short-circuiting devices and it has particular relation to centrifugally-operated mechanisms for use with relatively small dynamo-electric machines to effect a repulsion operation during the starting period and an induction operation during the normal operating period thereof.

One of the objects of my invention is to provide a short-circuiting device, of the character described, which comprises relatively few parts, is simple in construction and operation, is very compact in arrangement and may be manufactured at a relatively small expense.

A further object of my invention is to provide a device, of the character described, which embodies a plurality of substantially spherical contact members that are loosely mounted in suitable tracks or guides for movement into, and out of, short-circuiting engagement with the segments of a commutator cylinder, the spherical contact members being capable of rotating freely between the guides and about constantly changing axes to effect an even distribution of wear.

A further object of my invention is to provide a device, of the character described, in which the several movable contact members are retained in position by means of a cage or housing that tends to resiliently maintain the contact members out of short-circuiting engagement with the commutator segments when the machine is either stationary, or when it is operating at a very low initial speed in order to effect a repulsion operation thereof.

In the accompanying drawing,

Figure 1 is a view, partially in side elevation and partially in vertical longitudinal section, of a dynamo-electric machine embodying a short-circuiting device constructed in accordance with my invention.

Fig. 2 is an enlarged vertical longitudinal sectional view of the short-circuiting device illustrated in Fig. 1.

Fig. 3 is a vertical transverse sectional view taken on line III—III of Fig. 2 and illustrating the movable contact-retaining member or cage in elevation.

Referring to the drawing, a dynamo-electric machine, embodying a short-circuiting device constructed in accordance with my invention, is illustrated as comprising a stator frame 1 that is provided with end bells 2. A rotor shaft 3 is journaled in bearings 4 that are provided on the end bells 2 and carries a commutator cylinder 5.

The commutator cylinder preferably comprises a plurality of commutator bars or segments 6 that are mounted upon, and are partially embedded in, a body portion 7, of insulating material which is molded, or otherwise suitably secured, upon a sleeve member 8.

A contact-retaining member or cage, indicated, as a whole, at 9, is slidably mounted upon the shaft 3, for axial movement, and comprises a hub portion 10 that is provided with a substantially conical wall portion 11. The large-end diameter of the wall portion 11 of the retaining member 9 is substantially equal to that of the commutator cylinder 5 and, to a certain extent, the wall portion shields the exposed end portions of the commutator segments 6 from dust, oil or other foreign matter that might otherwise accumulate thereon.

The inner surface of the wall 11 is provided with a plurality of equally-spaced radially extending channels or grooves 12, within each of which a spherical contact member 13 is mounted for radial movement under the action of centrifugal force, as will be hereinafter set forth.

The retaining member 9 is resiliently biased in the direction of the commutator cylinder 5 by means of a coiled spring 14, which embraces the shaft 3 between the hub portion 10 of the rotating member 9 and a collar 15 that is suitably fixed to the shaft 3.

When the machine is either stationary or is operating at a very low peripheral speed, the inclined wall portion 11 of the retaining member 9, by reason of the action of the spring 14, maintains the contact members 13 out of engagement with the extremities of the commutator segments 6 and in a position contiguous to the insulating body portion 7 of the commutator cylinder.

The hub portion 10 of the retaining mem-

ber 9 extends inwardly further than the wall portion 11 and abuts against the sleeve 8 of the commutator cylinder 5, when the retaining member 9 is moved to its innermost position under the action of the spring 14 to maintain the periphery of the wall 11 in spaced relation with respect to the ends of the commutator segments 6.

When the accelerating machine armature 10 attains a predetermined peripheral velocity, the centrifugal force, acting upon the members 13, will increase to such an extent that they will be moved radially outwardly between the commutator cylinder 5 and the inclined wall 11 of the retaining member 9 to actuate the latter, in an axial direction, against the action of the spring 14. As the contact members 13 move outwardly under the action of centrifugal force, they will move out of engagement with the insulating portion 7 of the commutator cylinder 5 and into engagement with the extremities of the commutator segments 6.

When the members 13 occupy this outermost position, they bridge the space between the commutator segments 6 and the retaining member 9 to establish a short-circuit therebetween. The machine will, consequently, operate as an induction motor throughout the normal operating range thereof or as long as the centrifugal force acting on the members 13 is sufficient to overcome the force exerted by the spring 14. As soon, however, as the speed of the machine diminishes sufficiently to permit the force exerted by the spring 14 to overcome the centrifugal force acting upon the members 13, the retaining member 9 will be moved inwardly by the spring; that is, toward the commutator cylinder. This inward movement of the member 9 will cause the inclined wall 11 to force the contact members 13, radially inward, with a camming action, out of short-circuiting engagement with the commutator segments 6 and into their initial inactive positions in contact with the insulating portion 7. The machine will then function as a repulsion motor, as hereinbefore set forth.

By means of the above-described construction, a very compact and efficient short-circuiting mechanism is provided that embodies comparatively few parts, which may be easily manufactured and assembled.

I claim as my invention:

1. A short-circuiting device for dynamo-electric machines of the commutator type comprising a short-circuiting member adapted to be carried by said machine and in spaced relation with respect to the commutator cylinder thereof, and a substantially spherical contact member adapted to be confined between said short-circuiting member and said commutator cylinder for movement, both about constantly changing

axes and for movement in a radial direction into and out of short-circuiting engagement with the segments of said commutator cylinder and said short-circuiting member

2. A short-circuiting device for a dynamo-electric machine comprising a shaft, a commutator cylinder mounted on said shaft and having a body portion of insulating material and a plurality of commutator segments carried thereby, an axially movable member of conducting material mounted on said shaft and embodying an inclined wall portion provided with a plurality of radially extending channels and a plurality of substantially spherical contact members loosely mounted in said channels for movement about constantly changing axes and adapted to engage the insulated body portion of said commutator cylinder when said machine is operating at relatively low starting speeds and to move outwardly under the action of centrifugal force into engagement with said commutator segments to establish a short-circuit between said segments and said axially movable member when the machine attains a predetermined higher speed.

3. A short-circuiting device for a commutator-type dynamo-electric machine comprising a member adapted to be mounted for axial movement upon the shaft of said dynamo-electric machine and provided with an inclined wall portion of conducting material and a hub portion adapted to abut against the commutator cylinder to maintain said wall in spaced relation with respect to the segments thereof, a plurality of radially extending tracks provided on said axially movable member and a substantially spherical contact member loosely mounted in each of said tracks for movement about constantly changing axes and adapted to be moved radially outward under the action of centrifugal force into engagement with said commutator segments to bridge the space between said segments and said axially movable member to establish a short-circuit therebetween.

4. A short-circuiting device for a commutator-type dynamo-electric machine comprising a cage adapted to be mounted upon a shaft of said dynamo-electric machine and provided with an inclined wall portion of conducting material and a hub portion adapted to abut against the commutator cylinder to maintain said wall in spaced relation with respect to the segments thereof, a plurality of radially extending tracks provided on the wall portion of said cage, and a conducting ball loosely mounted in each of said tracks for movement about constantly changing axes and adapted to be moved radially outward under the action of centrifugal force into engagement with said segments and said cage to establish a short-circuit therebetween.

5. A short-circuiting device for a commutator-type dynamo-electric machine comprising a member adapted to be mounted upon the shaft of said dynamo-electric machine and provided with a substantially conical wall portion having a plurality of equally spaced radially extending channels therein, and a substantially spherical contact member loosely mounted in each of said channels for movement about constantly changing axes and adapted to be moved radially outward under the action of centrifugal force and into engagement with said commutator segments to bridge the space between said segments and said axially movable members to establish a short-circuit therebetween. 25
6. A short-circuiting device for a dynamo-electric machine comprising a member adapted to be mounted for axial movement upon the shaft of said dynamo-electric machine and provided with an inclined wall portion of conducting material and a hub portion adapted to abut against the commutator cylinder to maintain said wall portion in spaced relation with respect to the segments thereof, a plurality of radially extending tracks provided in said member, a ball of conducting material loosely mounted in each of said tracks for movement about 30 constantly changing axes and adapted to be moved radially outward under the action of centrifugal force and into engagement with said commutator segments to bridge the space between said segments and said axially movable member to establish a short-circuit therebetween, a collar fixed to said shaft, and a spring embracing said shaft and disposed between said collar and said axially movable member and adapted to 35 yieldably maintain said balls out of short-circuiting engagement with said commutator segments when said machine is operating at relatively low speeds. 40
- In testimony whereof, I have hereunto 45 subscribed my name this 8th day of August, 1922.

GEORGE H. GARCELON.
